(57) **CLAIM**

The ornamental design for an optical sight reticle, as shown and described.

DESCRIPTION

FIG. 1 is a front view of an optical sight reticle showing my new design, the dot dot dash lines depicting portions of the optical sight reticle that form no part of the claimed design; FIG. 2 is a rear view of the optical sight reticle, the dot dot dash lines depicting portions of the optical sight reticle that form no part of the claimed design;

FIG. 3 is a right side view of the optical sight reticle and being the same as a left side view, top view and bottom view thereof, the dot dot dash lines depicting portions of the optical sight reticle that form no part of the claimed design; and, FIG. 4 is a front perspective view of the optical sight reticle, the dot dot dash lines depicting portions of the optical sight reticle that form no part of the claimed design.

1 Claim, 3 Drawing Sheets---
